UNITED STATES PATENT OFFICE.

NILS A. WAHLBERG, OF WILKINSBURG, PENNSYLVANIA, ASSIGNOR TO WESTINGHOUSE ELECTRIC & MANUFACTURING COMPANY, A CORPORATION OF PENNSYLVANIA.

CONDUCTOR CLAMP.

Application filed April 12, 1927. Serial No. 183,086.

My invention relates to conductor clamps and particularly to clamps for holding high-voltage, transmission-line conductors.

One object of my invention is to provide a device of the above-indicated character that shall seat and clamp each of diverging or angularly-related portions of a bent conductor.

Another object of my invention is to provide a conductor clamp that shall comprise 10 few parts and be easy to manipulate.

Another object of my invention is to provide a transmission-line clamp of the dead-end type that shall effectively secure both the line and depending portions of the line 15 conductor.

A further object of my invention is to provide a clamp that shall be simple and durable in construction, economical to manufacture and effective in its operation.

20 In transmission-line practice, it has been usual to provide the so-called dead-end clamps with clamping means on the main bodies, but none on the diverging conductor seats thereof.

25 It has also been usual to provide a separate link member for connecting the clamp to an insulator. The above-mentioned features permit movement of the conductor relative to its diverging seat and require the use of a 30 certain number of parts.

It is my aim to prevent such movement, to 35 reduce the number of parts and to provide a clamp that is simple, strong, economical and an improvement in other ways over clamps heretofore employed.

Accordingly, in practicing my invention, I provide a clamp comprising a main clamping portion and a mounting portion that are 40 so integrally united and disposed in alignment, a diverging portion to which the conductor is so secured, retaining lips that are so constructed and disposed relative to the other parts and other features that are so embodied in the structure as to attain the 45 purposes set forth.

Figure 1, of the accompanying drawing, is a side elevational view of a transmission-line or conductor clamp constructed in accordance with my invention.

50 Fig. 2 is a top plan view of the device shown in Fig. 1, and

Fig. 3 is an enlarged view taken along the line III—III of Fig. 1.

The device comprises, in general, a member 2 having integrally united thereto, a main clamping or channel portion 3, a mounting portion 4, a portion 5 that diverges from the portion 3, web portions 6 and 7, a pair of lips 8, a lip 9, a clamp 10 on the web 7 and a main clamping member or members 12 on the portion 3.

The portions 3 and 4 are substantially aligned with each other, except that the portion 3 is at the under side of a straight portion 14 of a conductor having a diverging or bent portion 15, and the portion 4, or at least, a terminal eye or clevis portion 16 thereof, is preferably centered relative to the axis of the conductor portion 14.

The web or reinforcing portion 6 extends 70 along the under central portion of the channels between the downwardly curved portion 5, adjacent to the lip 9, and a similarly downwardly curved portion 11 between the lips 8.

The lips 8, adjacent to one end of the channel 75 3, and the portions 4 and 9, adjacent to the other end thereof, serve to render the channel deeper adjacent to the ends than at its intermediate portion whereon the member or members 12 are secured in position, by bolts 80 17 and nuts 18.

The clamp 10 preferably comprises an ordinary U-bolt that is secured to the web 7, by nuts 19 at the opposite side of the web. This arrangement of parts serves to prevent movement of the conductor portion 15 relative to the seat portion 5.

The portion 4 is extended beyond the portion 5 to take the place of the usual separate connecting link employed in devices of this 90 kind and the web 7, which reinforces the portion 5, is shaped to provide proper clearance between the clamp and an insulator (not shown) to which the portion 16 is to be attached.

95 By the structure described, a clamp is provided which comprises few parts, is simple, compact and durable in construction, is easy to manipulate and has other qualities, such as economy of manufacture and effective operation.

While I have shown and described a particular form of my invention, changes may be effected therein without departing from the spirit and scope thereof, as indicated by the 100 accompanying claims.

I claim as my invention:

1. A conductor clamp comprising a body member including angularly-related, conductor-receiving seat portion and a mounting portion extending from one side only of said body member to a position in substantial alignment with one of said portions, and means on each of the said angularly-related portions for clamping a conductor.
- 10 2. A conductor clamp comprising a body member including angularly-related, conductor-receiving seat portions, a conductor-retaining lip adjacent to the outer end of each of said portions and a mounting portion extending from one side only of said body member to a position in substantial alignment with one of said portions, and means on each of said portions for clamping a conductor.
- 15 3. A conductor clamp comprising a member having a substantially straight elongated portion along a section of one side of which a conductor is to be clamped, a conductor-retaining lip at one end of said portion, a clamp mounting portion at the other end of said portion, and a laterally-projecting portion between said section and said mounting portion for seating the conductor.
- 20 4. A conductor clamp comprising a member having a substantially straight elongated portion along a section of one side of which a conductor is to be clamped, a conductor-retaining lip at one end of said portion, a clamp mounting portion at the other end of said portion, a laterally-projecting portion between said section and said mounting portion for clamping the conductor on said laterally-projecting portion.
- 25 5. A conductor clamp comprising a member having a substantially straight elongated portion along a section of one side of which a conductor is to be clamped, a conductor-retaining lip at one end of said portion, a clamp mounting portion at the other end of said portion, a laterally-projecting portion between said section and said mounting portion for seating the conductor, and a retaining
- 30 6. A conductor clamp comprising a member having a substantially straight elongated portion along a section of one side of which a conductor is to be clamped, a conductor-retaining lip at one end of said portion, a clamp mounting portion at the other end of said portion, a laterally-projecting portion between said section and said mounting portion for seating the conductor, a retaining lip for the conductor on said laterally-projecting portion.
- 35 7. A conductor clamp comprising a member having a straight conductor-receiving portion for positioning under the conductor, a pair of retaining lips at one end of said portion at opposite sides of the conductor, an integral mounting portion in substantial alignment with said portion at the other end thereof, a widely curved conductor-seat portion diverging laterally from said first portion intermediate the same and the outer end of said mounting portion, a retaining lip on said diverging portion, a web portion extending between the outer end of the diverging portion and the outer end of said mounting portion, and means co-operating with said web for holding the conductor in position.
- 40 8. A conductor clamp comprising a channel portion for positioning under a conductor, longitudinally-spaced portions curving downwardly from said portion, and a reinforcing web extending along the under side of the channel portion between said curved portions.
- 45 9. A conductor clamp comprising a channel portion, a pair of retaining lips adjacent to one end thereof, a single retaining lip adjacent to the other end of the channel at one side thereof and means adjacent to said single lip at the opposite side of the channel for mounting the clamp.

In testimony whereof, I have hereunto subscribed my name this 8th day of April, 1927.

NILS A. WAHLBERG.
